United States Patent Office.

S. D. TRIPP, OF LYNN, MASSACHUSETTS.

Letters Patent No. 81,707, dated September 1, 1868; antedated August 21, 1868.

IMPROVED REVERSING CUTTING-MACHINE.

The Schedule referred to in these Letters Patent and making part of the same.

TO ALL WHOM IT MAY CONCERN:

Be it known that I, S. D. TRIPP, of Lynn, in the county of Essex, and State of Massachusetts, have invented a new and improved Tool-Reversing Cutting-Machine; and I do hereby declare that the following is a full, clear, and exact description thereof, which will enable those skilled in the art to make and use the same, reference being had to the accompanying drawings, forming part of this specification.

This invention relates to a new and improved machine for cutting out, from fabrics or stock, various articles which have curved sides, such, for instance, as the soles of boots and shoes; and it consists in having the stock, to which the cutters are attached, arranged in such a manner that in the operation of the machine the cutters may be reversed, so that reversed curves may be cut consecutively, and also the position of a cutter changed or reversed at each cut, so as to admit of economy in stock, the heel of one sole being at the side of the front portion of the adjoining one, as hereinafter fully shown and described.

In the accompanying sheet of drawings—

Figure 1 is a front view of my invention.

Figure 2, a vertical section of the same, taken in the line x x , fig. 1.

Figure 3, a horizontal section of the same, taken in the line y y , fig. 1.

Figure 4, a view of the inner side of a plate pertaining to the same.

Figure 5, a face view of a cutter pertaining to the same.

Similar letters of reference indicate corresponding parts.

A represents an upright framing, composed of two side pieces, a a , connected by suitable cross-rods.

In the upper parts of the side pieces a a there are made vertical oblong slots, c c , in which the journals d d of a shaft, B, are fitted, and allowed to work freely up and down, each journal being connected by a rod, C, to a crank, D, on a shaft, E, in the lower part of the framing, as shown clearly in fig. 1.

The shaft B has two cutters F F attached to it at opposite sides. These cutters are of the same shape or form, but have a reverse position relatively with each other.

In the present instance, these cutters are represented of a shape designed for cutting soles for boots and shoes, as will be seen by referring to fig. 3.

One of the journals d has a cross-head, G, on its outer end, armed with the pins e e , which project from it at right angles near its ends, as shown in fig. 1.

H is a vertical plate, which is connected to one of the side pieces a of the framing A by horizontal rods f, the plate H having vertical slots g made in it to receive the ends of the rods f.

This mode of attaching the plate H to the framing, admits of the former having a reciprocating motion imparted to it when necessary, and this is effected by means of a rod, I, connected at its upper end to the plate H, and at its lower end to a crank J, on a shaft K, in the lower part of the framing.

On the inner side of the plate H there are permanently attached three bars, g h i , two of them, g h , being similar in form, and having an inclined position relatively with each other, so as to approximate to a V-form, (see fig. 2,) each bar g h having a notch, j, made in its inner side or edge to receive the lower end of a guide, L, which is pivoted at the centre of bar i , and in the operation of the machine catches alternately into the notches j of the bars g h , said guide having a spring, k, bearing against it, which spring has a tendency to keep the guide in the notch of bar g .

The three bars g h i have such a position relatively with each other as to have a Y-shaped groove, a $\times$, between them, (see figs. 2 and 4.)

M represents a bar, pivoted at its lower end to the inner side of the plate H, and having a spring, l, bearing against it, to keep the upper end in contact with the upper end of bar g .

The pins e e , of the cross-head G, work in the groove a $\times$, between the bars g h i , and at the outer sides of the bars g h , and these bars, in connection with the pivoted guide L and the pivoted bar M, give to the cutter-shaft B, as it is moved up and down by the rotation of the crank-shaft E, a rotating motion, a half revolution

of shaft B being made during each stroke, that is to say, from the time it commences to rise until it nearly reaches the termination of its downward stroke. This is effected by the uppermost pin *e* being deflected or turned, as shaft E moves upward, by the guide L, which rests in the notch of bar *g*, over the top of and to the outer side of bar *h*, while the other pin *e* moves up at the outer side of bar *g*, between it and the pivoted bar M, forcing outward the latter, and passing into groove *a* above *g* and M, the latter, under the influence of spring *l*, instantly closing against the top of *g*, so that at the commencement of the downward movement of shaft E, which occurs when the pins reach this position, the pin which has just passed above *g* and M will be compelled to pass down the straight part of the groove *a*, forcing the guide L out of its way, the latter, after the pin has passed it, instantly resuming its position in bar *g*, under the influence of its spring, *k*.

By this arrangement, it will be seen that the cutters F E, on shaft B, are brought alternately in cutting position, the leather being placed on a bed, N, in the framing, (see fig. 3,) and one cutter cutting at one time the right side of a sole and the left side of the adjoining one, the other cutter, when it descends, cutting the right side of the last-named sole. This will be fully understood by referring to fig. 3, in which the cuts are shown in red.

The same intermittent rotating motion may be given the shaft B, without the reciprocating one, by operating the plate H, which may be done from shaft K. Other means, however, may be employed to operate it.

In this use of the machine, a cutter, O, is attached to the outer journal *d* of shaft B, said cutter having the form of a complete sole, so that stock will be saved by cutting it with the cutter reversed at each cut, the heel end of one cut being by the side of the front part of the succeeding one, and *vice versa*. By this means economy in stock is effected.

I would remark that when the up-and-down motion is given the shaft E, the plate H is held stationary, by securing the crank J in an upward position by means of a pin, *b*, (see fig. 1.)

I claim as new, and desire to secure by Letters Patent—

1. The means employed for operating the cutter-shaft B, to wit, the bars *g* *h* *i*, pivoted guide L, and the pivoted bar M on plate H, in connection with the cross-head G on the journal of shaft E, provided with the pins *e*, all arranged to operate substantially in the manner as and for the purpose set forth.

2. Attaching of the plate H to the framing A, in such manner as to admit of the same having a reciprocating movement imparted to it, substantially as shown and described.

S. D. TRIPP.
